UNITED STATES PATENT OFFICE.

EDMUND J. GREIVE, OF LOS ANGELES, CALIFORNIA.

CASKET.

Application filed June 27, 1924. Serial No. 722,690.

This invention relates to burial caskets and consists of the novel features herein shown, described and claimed.

An object is to make a two piece metal 5 burial casket adapted to be cheaply made and easily sealed.

Other objects and advantages will appear from the drawings and specification.

The drawings illustrate the construction 10 of a burial casket embodying the principles of my invention.

Figure 1 is a side elevation of the casket.

Fig. 2 is an enlarged vertical cross section on the line 2—2 of Fig. 1 and looking in the 15 direction indicated by the arrows.

Fig. 3 is a fragmentary perspective of one of the clamps for holding the parts together.

The details of construction shown in the 20 drawings are as follows:

The lower part 1 of the casket has a finished level upwardly projecting seat or rim 2 all the way around. The upper part 3 of the casket has a channel shaped recess 4 all 25 the way around with a finished seat 5 at the bottom of the channel, and a gasket 6 of rubber, cork, or other suitable material is placed upon the seat 2 to be engaged and compressed by the seat 5 so as to make a 30 tight joint between the parts 1 and 3. The part 3 is connected to the part 1 at one side by hinges 7. Hooks 8 project downwardly from the part 3 at the opposite side from the hinges 7. Attaching plates 9 are secured 35 to the part 1 in the vertical planes of the hooks 8. Levers 10 are pivotally connected to ears 11 projecting outwardly from the plates 9 by pins 12 and hooks 13 are connected to the levers 10 by pivots 14, and 40 when the levers 10 are swung upwardly the hooks 13 interlock with the hooks 8, and when the levers 10 are swung downwardly the pivots 14 pass inwardly beyond the pivots 12 and lock.

45 A glass plate 15 is securely sealed in an opening 16 to the top of the part 3 so that the interior of the casket may be viewed through the plate 15. A cover 17 is re-

movably mounted upon the part 3 to cover the glass 15 and make a finished appearance. 50 The parts 1, 3 and 17 are formed of metal.

The lower part of the casket is formed with a double walled hollow rim 20 having an outer fold 21 of the walls 22, which is preferably welded along the line 23, thereby 55 forming a stiff and rigid seat, 2, which is flat on its upper surface 24 and sloped outwardly therefrom to the fold 21.

The intermediate part 3 is constructed of a substantially flat surfaced inner wall 26 60 and a curved outer wall 27 forming a rigid construction for the seat 5 by placing this bore inside and outside. The upper part of the wall 27 has a groove 28 in which extends the flange 29 secured to the double 65 walled cover 17, the outer wall 30 preferably being curved and the inner wall 31 being flat. The plate of glass 15 rests on the shoulders 32 and is tightly secured thereon by a bead 33. 70

Thus I have produced a casket constructed of metal and consisting of two main parts having complementary seats, gaskets upon the seats, and means for securing the parts together to compress the gaskets and make 75 tight joints.

Various changes may be made without departing from the spirit of the invention as claimed.

I claim:

A casket comprising in combination a lower part having a hollow double walled rim formed by bending the upper part of the wall of the casket thereover, forming a substantially flat seat at the rim, an upper section of the casket having a double wall with a channel-shaped recess at its lower edge, a gasket therein between the seat and the recess, a groove at the upper part of the upper section, a cover having a depending 85 flange engaging the groove and means to clamp the lower and the upper section together.

In testimony whereof I have signed my name to this specification.

EDMUND J. GREIVE.
